UNITED STATES PATENT OFFICE.

MALCOLM C. ROSS, OF PHILIPSBURG, MONTANA.

LOCOMOTIVE-FEED-WATER HEATER.

989,055.

Specification of Letters Patent. Patented Apr. 11, 1911.

Application filed April 27, 1909. Serial No. 492,507.

To all whom it may concern:

Be it known that I, MALCOLM C. ROSS, a citizen of the United States, residing at Philipsburg, in the county of Granite and State of Montana, have invented certain new and useful Improvements in Locomotive-Feed-Water Heaters, of which the following is a specification, reference being had to the accompanying drawings.

This invention is a feed water superheater for the boilers of locomotives and stationary furnaces.

The object of the invention is to provide a simple and practical means for utilizing the heat from the cinders, smoke and gases of a boiler furnace for raising the temperature of water fed to the boiler and thereby effect a saving of fuel and prolong the life of the boiler.

With the above and other objects in view, the invention consists of the novel features of construction and the combination and arrangement of parts hereinafter fully described and claimed, and illustrated in the accompanying drawings, in which—

Figure 1 is a side elevation of a portion of a locomotive showing parts of its smoke arch broken away to illustrate my improved water superheater; and Fig. 2 is a detail vertical section taken on the plane indicated by the line 2—2 in Fig. 1.

The preferred embodiment of my invention illustrated in the drawings is especially adapted for use in connection with a locomotive boiler and it is arranged in the smoke box or arch beneath the smoke stack.

In the drawings, 1 denotes the body of the boiler having at its front end a flue sheet 2 and smoke box or arch 3. In the bottom of the latter is arranged the steam exhaust nozzle 4 from which escapes the exhaust from the engine cylinders to create a draft through the smoke arch 3 and the smoke stack 5 which projects from the top of said arch.

6 denotes a water feed pipe leading from the injector and extending to the front portion of the smoke arch 3 within which is arranged a spiral pipe coil 7. Said coil, in effect, forms a lining for the front end of the smoke arch and its inlet end 8 extends through the casing or wall of the boiler and is connected to a check valve casing 9, which latter is arranged upon the forward end of the feed pipe 6. If desired, the feed pipe 6

may be duplicated on the other side of the boiler, as indicated at 6^a, and the check valve casing 9^a on this pipe may be connected to a T-connection 10 with the outermost member of the coil 7.

For the purpose of directing the cinders, smoke and hot gases from the flue sheet 2 against the members of the coil 7 a baffle plate 11 is arranged in the smoke box or arch 3, as clearly shown in Fig. 1. Said plate has a downwardly and forwardly inclined vertical portion and a substantially horizontal portion through which latter the nozzle 4 projects. The forward end of the horizontal portion of the baffle plate is down-turned as indicated in dotted lines in Fig. 2 so that the heat and products of combustion will be deflected against the lower portion of the coil 7, and the outer or front end of the smoke arch, which latter will serve to deflect the heat and products of combustion rearwardly. Arranged on the front face of the upright portion of the baffle plate 11 is a second coil 12 consisting, preferably, of connected parallel pipes, as shown more clearly in Fig. 2. The lowermost end of the coil 12 is connected by a horizontally disposed, forwardly and rearwardly extending pipe 13 to the rear end of the coil 7 and the upper or discharge end 14 of the coil 12 extends rearwardly and is screwed into the flue sheet 2 so that it communicates with the interior of the boiler. By arranging the coil 12 in the manner described, it will be seen that smoke and gases after striking against the front end of the smoke arch 3 and contacting the portions of the coil 7 will be deflected rearwardly against the portions of the coil 12 to further utilize the heat of such smoke and gases to superheat the water passing through the coil.

At the bottom portion of the foremost member of the coil 7, and, if desired, at other points in said coil and also in the coil 12, may be provided openings closed by screw plugs 15. These openings and plugs are provided for the purpose of permitting mud, and scale to be blown out of the superheater when necessary.

While the drawings show the coils as composed of connected sections of pipes, it will be understood that such coils may be cast from iron or steel.

It will also be understood that slight changes in the form, proportion and ar-

angement of parts and in the details of construction may be resorted to within the spirit and scope of the invention.

Having thus described the invention what is claimed is:

A steam locomotive boiler having a smoke box at one end in advance of the front flue sheet, a smoke stack leading from the upper side of said smoke box, and an exhaust steam discharge nozzle extending upwardly in the lower side of said smoke box, a circular coil of pipe in the front end of said smoke box, a zigzag inclined coil in the rear portion of the smoke box, spaced from said flue sheet, connected to the water space of the boiler and also connected to the said front end coil, a feed water pipe connected to said front end coil, and a baffle in the smoke box, having an inclined rear portion between the zigzag coil and the flue sheet, the upper edge of

said inclined rear portion extending rearwardly to said flue sheet, the said baffle also having a forwardly extending lower horizontal portion through which the exhaust steam discharge nozzle extends, and terminating in a forwardly and downwardly inclined front portion extending into the lower portion of said front end coil, said baffle directing the products of combustion from the boiler flues downwardly and forwardly in the rear and lower portions of the smoke box and rearwardly through the front end coil and against the said zigzag coil substantially as described.

In testimony whereof I hereunto affix my signature in the presence of two witnesses.

MALCOLM C. ROSS.
